SWAGING APPARATUS

Filed Sept. 14, 1926

UNITED STATES PATENT OFFICE

PAUL A. NELSON, OF DENVER, COLORADO, ASSIGNEE, BY MESNE ASSIGNMENTS, TO THE GARDNER-DENVER COMPANY, OF QUINCY, ILLINOIS, A CORPORATION OF DELAWARE

SWAGING APPARATUS

Application filed September 14, 1926. Serial No. 135,436.

The present invention relates to swaging die apparatus, and while particularly intended for use as part of drill-forming and sharpening mechanism, may be employed independently thereof.

In the accompanying drawings:—

Fig. 1 is a vertical sectional view through one embodiment of the invention,

Fig. 2 is a view in elevation at right angles to Fig. 1 and showing the valve casing in section,

Fig. 3 is a horizontal sectional view on the line 3—3 of Fig. 2,

Fig. 4 is a vertical cross-sectional view on the line 4—4 of Fig. 2, and

Fig. 5 is a detail sectional view substantially on the line 5—5 of Fig. 1.

In the embodiment disclosed, a base 6 is employed, on which is located a standard 7.

This standard is provided in the upper portion of one side with a seat 8, in which is fitted one side of a vertical cylinder 9 that overhangs a bed 10 formed upon the base at one side of the standard 7. In the cylinder 9 is located a vertically reciprocating piston 11, having a reduced downward extension 11^a that projects below the lower end of the cylinder. The piston head is thus provided with an upper end surface or pressure area 12 and a lower shoulder, forming an oppositely disposed pressure area or surface 13, the latter being of less extent than the upper surface 12.

The lower end of the extension 11 is provided with a socket 14 that receives the shank

15 of a swaging die 16. A coacting swaging die 17 is located on the bed 10, the upper die 16 obviously moving downwardly into coaction with the lower die 17 and upwardly out of coaction therewith, being carried by the piston. The lower die 17 has in its under face a groove 18, and the bed 10 has in its upper face a groove 19 alined with the groove 18. This forms an opening through which a clamping bolt 20 passes, the said clamping

45 bolt having a head 21 that secures in place a clamping plate 22.

Motive fluid for effecting the actuation of the piston is supplied from any suitable source, through a passageway 23 that extends vertically in the standard 7 and com-

municates with a branch 24 formed in the adjacent side of the cylinder 9. The branch 24 opens into the lower portion of the cylinder below the lower pressure surface 13. Secured to the side of the standard 7 opposite to that on which the cylinder 9 is mounted, is a valve casing 25 and leading from the supply passageway 23 is a supply branch 26 that opens into a supply groove 27 formed around the chamber 28 in the valve casing. Another groove 29, located alongside the groove 27, is in communication by means of a passageway 30 with the upper end of the cylinder above the piston 11^a. A third annular groove 31, located next to the groove 29, is in communication with an exhaust passageway 32 opening to atmosphere. In the valve chamber 28 is a reciprocatory plunger valve 33 having end heads 34 and 35 and a central head 36. The heads 34 and 35 close the ends of the valve chamber, while the head 36 is movable to positions to cut off communication between the adjacent grooves 27 and 29 and 29 and 31. This plunger valve is connected by a link 37 with an operating hand crank 38 mounted as shown at 39 on the standard.

It will be understood that when motive fluid, as air, is supplied to the passageway 23, it will have constant access to the lower portion of the cylinder and operate constantly against the lower pressure surface 13 to raise the piston. Motive fluid will also have access to the groove 27, but if the valve is in the position shown in Figures 2 and 3, the motive fluid will be cut off from the passageway 30. If the valve is moved to the right however, communication will be established between the grooves 27 and 29, and consequently motive fluid flowing through the passageway 30, will enter the upper end of the cylinder, and operating on the surface 12 of greater area, will overcome the resistance of the fluid against the surface 13 and move the piston downwardly with speed and force, thus causing the die 16 to deliver a swaging blow to the die 17. When the valve is moved to the left, this communication will be again cut off and then grooves 29 and 31 will be brought into communication so that the motive fluid

above the piston can exhaust through the passageway 30, grooves 29 and 31, and exhaust port 32.

From the foregoing, it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What I claim is:

- 15 1. In swaging apparatus, the combination with a base having a standard, of a vertical cylinder mounted one one side of the standard, a valve casing mounted transversely of and on the other side of the standard below its upper end, a piston in the cylinder having an upper and a lower pressure surface, the former being greater than the latter, a passageway in the standard from the valve casing to the upper portion of the cylinder, a supply passageway in the standard having branches leading to the valve casing and to the lower portion of the cylinder, a valve in the valve casing controlling communication between the branch thereto and the passageway therefrom, and coacting swaging dies, one of which is carried by the lower end of the piston and is located below the lower end of the cylinder.
- 20 2. In swaging apparatus, the combination with a base having a bed and a cylinder and piston overhanging the bed, of a swaging die carried by the piston, a coacting swaging die located on the bed, said bed and latter swaging die having alined grooves in and across their associated faces, a bolt having its shank located in the alined grooves, and a holding clamp for the die engaged therewith and mounted on the bolt between the same and the bolt head.
- 25 3. In testimony whereof, I affix my signature.
PAUL A. NELSON.
